UNITED STATES PATENT OFFICE.

ABRAHAM M. YEAKEL, OF PERKASIE, PENNSYLVANIA.

WATCH-CASE PENDANT.

SPECIFICATION forming part of Letters Patent No. 317,914, dated May 12, 1885.

Application filed February 12, 1885. (No model.)

To all whom it may concern:

Be it known that I, ABRAHAM M. YEAKEL, a citizen of the United States, and a resident of Perkasie, in the county of Bucks and State of Pennsylvania, have invented certain new and useful Improvements in Watch-Case Pendants; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a portion of the case-center of a watch-case having my improved pendant. Fig. 2 is a sectional view taken vertically through the pendant. Fig. 3 is a vertical sectional view taken on the line *xx* in Fig. 2. Fig. 4 is a horizontal sectional view taken on the line *yy* in Fig. 3; and Fig. 5 is a perspective detail view, showing the several parts composing my improved watch-pendant separated or detached from each other.

The same letters refer to the same parts in all the figures.

This invention relates to pendants for watch-cases; and it has for its object to provide a pendant intended more especially for all classes of hunting-case watches, whether face or stem winders, and also for open-face stem-winders, which shall be simple in construction, inexpensive, and absolutely dust-proof.

With these ends in view the invention consists in the improved construction and combination of parts of the said watch-case pendant, which will be hereinafter fully described, and particularly pointed out in the claims.

In the drawings hereto annexed, A designates a pendant, to the lower end of which the case-center of the watch-case B is soldered or otherwise secured, and the sides of which are provided with recesses or sockets to receive the ends of the pendant bow-ring C. The pendant A is provided with an upward-extending neck, D, upon which is fitted a swiveled ring, G, which is securely retained by means of a collar, H, firmly secured upon the upper end of said neck. A perforation, I, extends through the pendant A, the upper part of which is enlarged, so as to form a shoulder, J, upon which is seated a spiral spring, K.

L designates a crown, the inner side of which is provided with a downward-extending stem, M, passing through the perforation I. Said crown is provided on its inside with vertical grooves N N, registering with lugs O O, extending laterally from the swiveled ring G, to which latter the said crown is secured by means of small screws P P. It will be seen that when this connection is made the spring K serves to force the crown L in an upward direction, thus forcing the swiveled ring G into contact with the collar H, and forming a practically dust-tight joint, which still leaves the crown L free to turn.

The lower or inner end of the push-pin M bears against the case-spring Q, which may thus be operated by simple pressure from the outside upon the crown L. By this arrangement the said case-spring also serves to force the crown L in an upward direction, thus reinforcing the spring K.

From the foregoing description, taken in connection with the drawings hereto annexed, the operation and advantages of this invention will be readily understood.

The construction is simple and effective for the purpose set forth, and the device may be readily applied to ordinary watch-cases.

Having thus described my invention, I claim and desire to secure by Letters Patent of the United States—

1. The combination of a pendant having an upward-extending neck, and provided with a vertical perforation, the upper part of which is enlarged, so as to form a shoulder, a spiral spring seated on said shoulder, a ring swiveled on the neck of the pendant and retained by a collar fixed at the upper end of the same, and a crown fitted over and attached to the swiveled ring, and having a stem extending through the perforation of the pendant, all arranged and operating substantially as and for the purpose herein set forth.

2. The combination of the pendant having an upward-extending neck, the swiveled ring having laterally-extending lugs, the fixed retaining-collar, the crown having interior grooves adapted to receive the lugs of the swiveled ring, and provided with a downward-extending stem, means for attaching the said crown to the swiveled ring, and a spring

arranged to force the said crown in an upward direction, substantially as and for the purpose herein set forth.

3. In a watch-case crown, the combination 5 of the pendant having a vertical perforation, the swiveled ring, the retaining-collar, the crown attached to the swiveled ring, and having a stem extending through the perforation of the pendant, a spiral spring arranged to 10 force the crown in an upward direction, the case-center of the watch-case secured to the lower end of the pendant, and the case-spring

bearing against and adapted to be operated by the lower or inner end of the stem extending downwardly from the crown, substantially 15 as and for the purpose herein set forth.

In testimony that I claim the foregoing as my own I have hereunto affixed my signature in presence of two witnesses.

ABRAHAM M. YEAKEL.
